United States Patent Office

Des. 182,926
Patented May 27, 1958

182,926

SERVING TABLE

Laurence B. Roeder, Los Angeles, Calif.

Application March 7, 1955, Serial No. 34,919

Term of patent 14 years

(Cl. D33—14)

Fig. 1 is a perspective view of a serving table embodying my new design, showing the side wings in a raised position and the drawer open;

Fig. 2 is a perspective view taken opposite Fig. 1 with the side wings closed; and

Fig. 3 is a fragmentary perspective view showing the serving table in fully open position.

I claim:

The ornamental design for a serving table, as shown.
